TOOL FOR PERFORMING ABRADING OR
POLISHING OPERATIONSHomer B. Miller, Gardiner, Maine, assignor to
United Shoe Machinery Corporation, Borough
of Flemington, N. J.

Application October 25, 1939, Serial No. 301,246

6 Claims. (Cl. 51—192)

This invention relates to tools for performing abrading or polishing operations and is herein illustrated and described as embodied in a roll suitable for buffing shoe bottoms. The roll illustrated herein like most rolls intended for this purpose provides a yieldable support for a buffing cover of sheet material.

It is an object of the present invention to provide an improved tool of the character under consideration. In accordance with a feature of the invention, the roll illustrated herein is provided with a flexible sleeve for supporting a buffing cover which sleeve is supported by a pair of members adapted to be mounted at its ends on a rotary shaft and urged apart resiliently to tension the sleeve. The supporting members as shown herein have tubular portions in telescoping relation to each other and are urged apart by a coil spring. In order to provide a further yielding support in addition to the tension of the flexible sleeve, an annular inflatable cushion surrounding the telescoping members is mounted within the sleeve.

These and other features of the invention comprising various combinations and arrangements of parts will be best understood from the following description of a preferred embodiment shown in the accompanying drawing, in which

Fig. 1 is a view mainly in longitudinal section; 30 and

Fig. 2 is a transverse sectional view taken on the line II—II of Fig. 1.

As shown in the drawing, the improved roll is adapted to be mounted upon a rotary shaft 10. Secured to the shaft 10 by a set screw 12 is a supporting member 14 having a tubular portion 16 fitted upon the shaft 10 and an outwardly extending flange or disc 18. The tubular portion 16 is externally threaded over a part of its length to accommodate an internally threaded cylinder 20 which, in effect, constitutes an adjustable extension of the tubular portion 16. The cylinder 20 at its outer end is provided with an outwardly extending flange 22 in the periphery of which are formed holes 24 to accommodate a wrench for turning the cylinder 20 upon the tubular portion 16. A second support 26 has a tubular portion 28 surrounding the portion 16 and the cylinder 20. The tubular portion 16 is of enlarged external diameter at a locality between the flange 18 and the adjacent end of the cylinder 20 to provide a bearing surface 30 for the end of the tubular portion 28. A key 31 extending inwardly from the member 28 engages a corresponding slot in the member 14 to prevent relative rotation. The re-

mainder of the tubular portion 16 is of reduced external diameter to provide an annular space between it and the tubular portion 28. The tubular portion 28 is of reduced internal diameter at a locality surrounding the cylinder 20 to provide a bearing surface 32 for the cylinder, the remainder of the tubular portion 28 being of enlarged internal diameter to provide an annular space between itself and the cylinder 20. The support 26 is provided also with a circular flange or disc 34 which is spaced axially a considerable distance from the disc 18.

Supported at its ends upon the discs 18 and 34 respectively is a sleeve 36 of tough woven fabric such as canvas. The end portions of the sleeve 36 are turned inwardly over the end faces of the discs 18 and 34 respectively and are clamped against said end faces by clamping rings 38 and 40 respectively. The clamping rings 38 and 40 are tightened against their respective discs by screws 42. Surrounding the cylinder 20 and surrounded by the tubular portion 28 is a coil compression spring 50 one end of which abuts an outwardly turned shoulder 52 on the cylinder 20 and the opposite end of which abuts an inwardly turned shoulder 54 on the support 26. The thrust of the spring 50 urges the supports 14 and 26 apart axially and thereby tensions the sleeve 36.

Surrounding the tubular portion 28 and enclosed within the sleeve 36 and the supporting discs 18 and 26 is an annular inflatable cushion 44 of rubber. This cushion is inflated by an ordinary tire valve 46 (Fig. 2) extending through a suitable opening formed in one of the adjacent end discs 18 or 34. Carried by the flexible sleeve 36 is a tubular cover 48 of sheet material such as emery cloth suitable for performing buffing operations. The cover 48, however, may consist of a polishing cloth or similar material in place of emery cloth.

It is evident that the tool body above described constitutes a unitary structure held together by the flexible sleeve 36. This structure may be applied endwise over the shaft 10 and clamped in position by the screw 12. The buffing sleeve 48 may then be applied endwise over the sleeve 36. In order to insure an internal gripping pressure against the buffing sleeve, the cushion 44 is then inflated. In operation the bulging of the flexible sleeve 36 under the pressure of the inflated cushion 44 is sufficient to insure rotation of the buffing sleeve 48 with the tool body. The pressure of the work against the tool is sustained not only by the air pressure within the cushion 44 but also by the tension induced in the flexible sleeve 36 by

the spring 50 which enables the operator to bear with considerable pressure against the work without danger of collapsing the sleeve 36. The thrust of the spring 50 may be increased or diminished as desired by turning the flange 22 with a suitable wrench.

Having thus described the invention, what I claim as new and desire to secure by Letters Patent of the United States is:

- 10 1. A buffing roll, comprising a flexible sleeve for supporting a buffing cover, a pair of members adapted to be mounted on a rotary shaft for supporting the ends respectively of said sleeve, one of said members being freely movable axially with respect to the other, and resilient means for urging said supporting members apart to tension said sleeve.
- 15 2. A buffing roll, comprising a flexible sleeve for supporting a buffing cover, a pair of members adapted to support the ends respectively of said sleeve and each having a tubular portion in telescoping relation to the tubular portion of the other member, one of said tubular portions being constructed and arranged for attachment to a rotary shaft, means for securing the ends of said sleeve to said members respectively, means for preventing relative rotation between the members of said pair, and a spring exerting an axial thrust between said members to urge said discs 30 apart and thus tension said sleeve.
- 20 3. A buffing roll, comprising a flexible sleeve for supporting a buffing cover, a support having a tubular portion adapted to be mounted on a rotary shaft, a support having a tubular portion surrounding the first-mentioned tubular portion, means for preventing relative rotation between said tubular portions while enabling one of said tubular portions to move axially relatively to the other, each of said supports having a circular outwardly extending flange, means for securing the ends of said sleeve to said flanges respectively, and a coil compression spring surrounding the first-mentioned tubular portion and surrounded by the second-mentioned tubular portion, said 35 supports having shoulders in abutting engagement respectively with the ends of said spring, whereby the thrust of said spring urges the flange of one support away from the flange of the other support to tension the flexible sleeve.
- 40 4. A buffing roll, comprising a flexible sleeve for supporting a buffing cover, a support having an

externally threaded tubular portion adapted to be mounted on a rotary shaft and having also at one end an outwardly extending circular flange, a cylinder threaded on said tubular portion to constitute an adjustable extension thereof, a support having a tubular portion slidable axially on the first-mentioned tubular portion and on said cylinder, the first-mentioned tubular portion being of enlarged external diameter at a locality between said flange and the adjacent end of said cylinder to provide a bearing surface for the second-mentioned tubular portion, and the second-mentioned tubular portion being of reduced internal diameter at a locality surrounding said cylinder to provide a bearing surface for the 15 cylinder, the second-mentioned support having an outwardly extending flange spaced axially from the first-mentioned flange, means for securing the ends of said sleeve to said flanges respectively, and a coil compression spring surrounding 20 said cylinder and surrounded by the second-mentioned tubular member, said cylinder having an external shoulder in abutting engagement with one end of said spring, and the second-mentioned support having an internal shoulder in abutting 25 engagement with the other end of said spring, whereby the thrust of said spring urges said flanges apart axially to tension said sleeve, the magnitude of said thrust being determined by adjustment of said cylinder on the first-men- 30 tioned tubular portion.

5. A buffing roll, comprising a flexible sleeve for supporting a buffing cover, a pair of members adapted to be mounted on a rotary shaft for supporting the ends respectively of said sleeve, 35 resilient means for urging said supporting members apart to tension said sleeve, and an inflatable cushion within said sleeve and surrounding the shaft to support the sleeve against the pressure of the work.

6. A buffing roll, comprising a flexible sleeve for supporting a buffing cover, a pair of telescoping members adapted to be mounted on a rotary shaft for supporting the ends of said sleeve respectively, a coil compression spring for urging 45 said members apart to tension the sleeve, and an inflatable annular cushion within said sleeve and surrounding said telescoping members to support the sleeve against the pressure of the work.
